UNITED STATES PATENT OFFICE

135,789

DESIGN FOR A BADGE OR THE LIKE

Raymond Robert Primozych, Denver, Colo.

Application March 16, 1943, Serial No. 109,764

Term of patent 7 years

To all whom it may concern:

Be it known that I, Raymond Robert Primozych, a citizen of the United States, residing at Denver, in the county of Denver and State of Colorado, have invented a new, original, and ornamental Design for a Badge or the like, of which the following is a specification, reference being had to the accompanying drawing, forming part thereof.

I claim:

The ornamental design for a badge or the like, substantially as shown.

RAYMOND ROBERT PRIMOZICH.
